F. W. MANN & M. L. CHAPPELL,
PROCESS FOR MAKING CHLORINATED HYDROCARBONS.
APPLICATION FILED APR. 16, 1915.

1,183,094.

Patented May 16, 1916.

UNITED STATES PATENT OFFICE.

FREDERICK WILLIAM MANN AND MARVIN LEE CHAPPELL, OF BERKELEY, CALIFORNIA, ASSIGNORS TO STANDARD OIL COMPANY, OF RICHMOND, CALIFORNIA, A CORPORATION OF CALIFORNIA.

PROCESS FOR MAKING CHLORINATED HYDROCARBONS.

1,183,094.

Specification of Letters Patent.

Patented May 16, 1916.

Application filed April 16, 1915. Serial No. 21,668.

To all whom it may concern:

Be it known that we, FREDERICK WILLIAM MANN and MARVIN LEE CHAPPELL, citizens of the United States, residing at Berkeley, 5 in the county of Alameda and State of California, have invented certain new and useful Improvements in Processes for Making Chlorinated Hydrocarbons, of which the following is a specification.

10 This invention relates to the production and separation of chlorinated hydrocarbons, and particularly to their production and separation from distillates of crude petroleum.

15 In carrying out the process, petroleum distillates are used which contain a high percentage of aromatic and unsaturated hydrocarbons, and which are acted upon by sulfuryl chlorid, forming the corresponding 20 chlorin compounds, such, for example, as—

1. $\text{RH} + \text{SO}_2\text{Cl}_2 = \text{RCl} + \text{HCl} + \text{SO}_2$.
2. $\text{RCH}=\text{CH}_2 + \text{SO}_2\text{Cl}_2 = \text{RCHClCH}_2\text{Cl} + \text{SO}_2$.

25 Reaction 1 shows the action of sulfuryl chlorid on the aromatic constituents.

Reaction 2 shows the action of sulfuryl chlorid on the unsaturated hydrocarbons. These are given merely as general type 30 actions, since the chlorin of the sulfuryl chlorid may also combine with some of the hydrocarbons in the oil in other ways, according to the temperature of and the constituents present in the distillates. These 35 chlorinated hydrocarbons are separated from the non-chlorinated saturated hydrocarbon oils by dissolving them in liquefied sulfur dioxid at a suitable temperature, which for the best results is one below 32 de-

40 gress Fahr. From the above it will be seen that for a brief statement of the nature of the process in its essentials, it may be said to consist in treating the distillates from crude petroleum 45 with sulfuryl chlorid dissolved in an excess of liquefied sulfur dioxid at a temperature below 32 degrees Fahr. This process is par-

ticularly applicable for obtaining chlorinated hydrocarbons from California petroleum 50 distillates or similar petroleum distillates, which carry from 1 to 5% olefinic hydrocarbons, such as octylene, nonylene, decylene and the like, and from 10 to 25% aromatic hydrocarbons such as xylene,

mesitylene, cymene, pseudo-cumene and the like. The chemical composition of the petroleum distillate to be treated is determined and the necessary amount of chlorin calculated. This calculated amount of chlorin is added to the liquefied sulfur dioxid forming 60 sulfuryl chlorid dissolved in an excess of liquid sulfur dioxid. The amount of liquid sulfur dioxid necessary also depends upon the chemical composition of the petroleum distillate to be treated. Petroleum distillates containing a high percentage of aromatic and olefinic hydrocarbons may require as much as two volumes of liquid sulfur dioxid and 5% by weight chlorin. For example, a petroleum distillate which contains 3% olefinic hydrocarbons and 20% aromatic hydrocarbons, requires $\frac{1}{10}$ of one pound of liquid chlorin dissolved in 21 pounds of liquid sulfur dioxid, for each 65 gallon of distillate. We do not confine ourselves to these proportions since we could use $\frac{1}{10}$ of a pound of chlorin dissolved in 15 or 24 lbs. of liquid sulfur dioxid.

70 We are aware that the art of making chlorinated hydrocarbons by the action of sulfuryl chlorid on coal-tar distillates is well known. The novelty of our invention, however, consists in the application of sulfuryl chlorid in the presence of an excess of sulfur dioxid, and applying the same to 80 petroleum distillates containing a high percentage of olefinic and aromatic hydrocarbons, which results in the formation and separation of chlorinated hydrocarbons. By the action of the sulfuryl chlorid we 85 form chlorinated olefinic and aromatic hydrocarbons, such as dichlor-octane $\text{C}_8\text{H}_{16}\text{Cl}_2$, dichlor-nonane $\text{C}_9\text{H}_{18}\text{Cl}_2$, dichlor-decane $\text{C}_{10}\text{H}_{20}\text{Cl}_2$, chlor-xylene $\text{C}_8\text{H}_9\text{Cl}$, chlor-mesitylene $\text{C}_9\text{H}_{11}\text{Cl}$, chlor-cymene $\text{C}_{10}\text{H}_{13}\text{Cl}$, chlor-pseudo-cumene $\text{C}_9\text{H}_{11}\text{Cl}$ and the like. The function of the large excess of liquid sulfur dioxid is to dissolve and separate the chlorinated hydrocarbons by the action 90 stated.

95 The process more particularly stated is as follows:—The oil to be treated is charged into a tank. Liquefied sulfur dioxid containing chlorin is added from the top, preferably by being sprayed. For example, one-half to two volumes of the liquefied sulfur dioxid containing the predetermined percentage of chlorin are used for each volume 100 105

2
of the oil to be treated. This treating mixture is made by adding the predetermined amount of chlorin, say 1% to 5%, by weight, to the liquid sulfur dioxid, under pressure, say of 75 to 100 pounds. The sulfuryl chlorid thus formed is dissolved in an excess of liquid sulfur dioxid. After introducing this mixture, the contents of the tank are agitated, this being best done by means of a 10 vacuum pump, communicating with the top of the tank, the vacuum causing some of the liquefied sulfur dioxid to vaporize, thus producing sufficient agitation, and at the same time lowering the temperature to the desired 15 point. The sulfur dioxid, which is thus vaporized, is condensed and recovered. When the oil under treatment has had sufficient agitation and the reaction is finished, the vacuum pump is stopped and the chlorinated 20 hydrocarbons dissolved in the liquefied sulfur dioxid settle to the bottom. In this way two layers are formed. The bottom layer of the treated oil is drawn off through a heat interchanger where it partially cools 25 down the incoming charge of oil which at this time is being delivered to a second treating tank, a companion of the first tank. From the heat interchanger the bottom layer enters a still in which the remaining sulfur 30 dioxid is distilled off, condensed and conducted to a storage tank for use again. The separated chlorinated aromatic and chlorinated unsaturated hydrocarbons can be used in the manufacture of dyes and other 35 chemical compounds for which they are particularly adapted. The top layer of the treated oil is then drawn off through a heat interchanger, where it partly cools down the liquid sulfur dioxid sulfuryl chlorid mixture which at the time is on its way into the 40 second treating tank. This top layer oil is run into a still, in which the sulfur dioxid is distilled off, condensed and conducted to the storage tank for use again. In some 45 cases, the top layer oil thus obtained is not sufficiently pure for the market, and it is necessary to treat it with a small amount of sulfuric acid.

The process will be more fully understood 50 by reference to the accompanying drawing in which the figure illustrates one form of an apparatus adapted for carrying it out.

1 and 2 are treating tanks.

3 is the oil supply pipe controlled by a 55 valve 4.

5 is a feed pump with which the supply pipe 3 communicates, and 6 is the charging pipe, which leads into the treating tank 1, by a branch 7 controlled by a valve 8, and 60 leads into the charging tank 2, by a branch 9 controlled by a valve 10.

11 is a storage tank for the mixture of sulfuryl chlorid and liquefied sulfur dioxid. From this storage tank leads a delivery pipe 65 12, controlled by a valve 13, said pipe ter-

minating in a branch 14 controlled by a valve 15, and entering the tank 1, its extremity being fitted with a spraying device 16. From the pipe 12, a similar branch 17 controlled by a valve 18, enters the tank 2 70 and is fitted with a spraying device 19.

20 is a compressor which on its suction side has a pipe 21, with a controlling valve 22. With this suction pipe 21 is connected a pipe 23, which, by a branch 24, having a 75 valve 25, communicates with the top of the tank 1, and by a branch 26, having a valve 27, communicates with the top of the tank 2. From the pressure side of the compressor 20 leads a pipe 28, which is coiled through 80 a condenser box 29, and then enters the storage tank 11. From the bottom of the tanks 1 and 2 issues a pipe 30, from which a pipe 31, with a valve 32, leads to a heat interchanger shell 33 in which the charging pipe 85 6 is coiled. From this heat interchanger shell issues a pipe 34 with a valve 35, said pipe leading to a pump 36, from which a pipe 37 with a valve 38 leads to a still 39 in which is a steam coil 40. From the still 90 39 leads a pipe 41, having a valve 42, to a second still 43, fitted with a steam coil 44. From the still 43 issues a valve controlled discharge pipe 45.

From the bottom of the tanks 1 and 2 is 95 issues a pipe 46 having a valve 47, said pipe leading to a pump 48 from which a pipe 49 extends to and communicates with a heat interchanger shell 50 in which the delivery pipe 12 is coiled. From this shell 50 leads 100 a pipe 51 having a valve 52, said pipe entering a still 53, in which is a steam coil 54. This still is connected by a pipe 55, having a valve 56, with a still 57 in which is a steam coil 58. The still 57 has a valve controlled 105 discharge pipe 59.

The suction pipe 21 of the compressor 20 connects with the still 43 by a branch pipe 60 having a valve 61, and it connects with the still 57 by a branch pipe 62 having a 110 valve 63.

From the pressure pipe 28 of the compressor 20 leads a pipe 64, which connects with the still 39 by a branch pipe 65 having a valve 66, and it connects with the still 53 115 by a branch pipe 67 having a valve 68.

The courses of the several fluids through the apparatus are indicated by the arrows. The method carried out in this apparatus is, in detail, as follows: Petroleum distillate, 120 supplied through pipe 3, is, by means of the pump 5, pipe 6 and branch pipe 7, charged into the treating tank 1. The storage tank 11 is charged with liquefied sulfur dioxid containing 1% to 5%, by weight, of chlorin. 125 This mixture is introduced into the tank 1 through the pipe 12, branch pipe 14 and spraying device 16. Then the compressor 20 is started, which taking suction through pipes 21 and 23 and branch pipe 24, reduces 130

the pressure in the tank 1, and causes a portion of the liquefied sulfur dioxid to vaporize, which lowers the temperature to the desired point, and, at the same time, agitates the tank contents thoroughly, so that there is an intimate contact between the oil and the chlorin mixture. The vaporized sulfur dioxid is taken off by the compressor and is passed through the pipe 28 coiled in the condenser 29, through which a constant flow of cold water is maintained. In this coil under sufficient pressure it becomes liquefied and flows into the storage tank 11. The heat of compression is neutralized by the cold water in the condenser. When the treated oil in the tank 1 has had sufficient agitation and has reached the desired temperature, the compressor 20 is stopped and the valve 25 at the branch 24 into the tank is closed. The mixture in said tank separates into two layers. The bottom layer, consisting of chlorinated aromatic oils, and chlorinated unsaturated hydrocarbons held in solution by the liquid sulfur dioxid, is drawn off through the pipes 30 and 31, into the heat exchanger shell 33, and at the same time the other treating tank 2 is charged by the pump 5 with fresh distillate for the next treatment. Thus in the charging pipe 6 and the shell 33 there is an exchange of heat between the incoming distillate and the outgoing chlorinated hydrocarbons and liquid sulfur dioxid. After this exchange of heat, the chlorinated liquid sulfur dioxid mixture is delivered by the pipe 34 to the pump 36, by which it is forced through the pipe 37 into the still 39. In this still, by means of the steam coil 40, the temperature is raised sufficiently to vaporize nearly all the liquid sulfur dioxid. The vaporized sulfur dioxid passes from the still 39, through the pipes 65 and 64 into the compressor pipe 28, in the condensing coil of which it is under sufficient pressure to be liquefied, and as a liquid it then runs into the storage tank 11.

In order to separate more completely the chlorinated bottom layer oil from the sulfur dioxid, it is drawn from the still 39, through the pipe 41 into the still 43, which is heated by the steam coil 44 and is kept under a partial vacuum produced through the compressor suction pipe 21 and the branch pipe 60. The top layer oil in the tank 1, is next taken off through the pipe 46, and by means of the pump 48 is passed through the pipe 49 into the heat exchanger shell 50, in which it partly cools down the liquid sulfur dioxid sulfuryl chlorid mixture, which is, at the same time, passing through the coil pipe 12 on its way to the second treating tank 2 to be delivered therein through the spraying device 19. From the exchanger shell 50, the top layer oil overflows through the pipe 51 into the still 53, wherein, under the heat from the steam coil 54, most of the remain-

ing sulfur dioxid is distilled off, and its vapor passing through pipes 67 and 64 enter pipe 28 and is condensed in the coil of said pipe in the water box 29, and thence as a liquid runs into the storage tank 11. In order to free more completely this top layer oil from sulfur dioxid, it is drawn from the still 53 through the pipe 55 into the still 57, which is heated by the steam coil 58 and is kept under partial vacuum through the pipes 62 and 21. From the still 57 the oil runs to a storage tank through the pipe 59, while the contents of the still 43 pass to their destination through the pipe 49.

If necessary the oil from still 57 is treated finally with a small amount of sulfuric acid, washed and neutralized according to the well known methods.

The separated chlorinated hydrocarbon oils are used in the dye industry; for fire extinguishers, and in the manufacture of various chemicals. The oil from which the chlorinated hydrocarbons have been removed, that is, the non-chlorinated saturated hydrocarbons, can be used for lamp oils, or for other purposes for which they may be adapted.

We claim:

1. That step in the process of making chlorinated hydrocarbons which consists in treating petroleum distillates with sulfuryl chlorid in the presence of liquefied sulfur dioxid.

2. That step in the process of making chlorinated hydrocarbons which consists in treating petroleum distillates with sulfuryl chlorid in the presence of liquid sulfur dioxid at temperatures below 32 degrees Fahr.

3. The process of making chlorinated hydrocarbons, which consists in first treating petroleum distillates with sulfuryl chlorid in the presence of liquefied sulfur dioxid to chlorinate the unsaturated and aromatic hydrocarbons present and to dissolve said chlorinated products; and then separating the resultant liquids.

4. The process of making chlorinated hydrocarbons, which consists in first treating petroleum distillates with sulfuryl chlorid in the presence of liquefied sulfur dioxid, at temperatures below 32 degrees Fahr., to chlorinate the unsaturated and aromatic hydrocarbon present and to dissolve said chlorinated products; and then separating the resultant liquids.

5. The process of making chlorinated hydrocarbons, which consists in first treating petroleum distillates with sulfuryl chlorid in the presence of liquefied sulfur dioxid to chlorinate the unsaturated and aromatic hydrocarbons present and to dissolve said chlorinated products; vaporizing sufficient of the sulfur dioxid, during said treatment, to produce a temperature of below 32 de-

2
grees Fahr.; and finally separating the resultant liquids.

6. The process of making chlorinated hydrocarbons, which consists in first treating petroleum distillates with sulfuryl chlorid in the presence of liquefied sulfur dioxid to chlorinate the unsaturated and aromatic hydrocarbons present and to dissolve said chlorinated products; vaporizing sufficient of the sulfur dioxid, during said treatment, to produce a temperature of below 32 degrees Fahr.; separating the resultant liquids; and finally separating the remaining sulfur dioxid from each of said resultant liquids.

15 7. The process of making chlorinated hydrocarbons which consists in first separately treating petroleum distillates in successive charges, with sulfuryl chlorid in the presence of sulfur dioxid, at temperatures

below 32 degrees Fahr., to chlorinate the 26 unsaturated and aromatic hydrocarbons present and to dissolve said chlorinated products; then separating the resultant liquids, and, in said separation, exchanging the 25 heat of the liquids of one charge, with the incoming petroleum distillates, and the chlorinated sulfur dioxid treating mixture of the succeeding charge; and, finally separating the sulfur dioxid from each of said resultant liquids.

In testimony whereof we have signed our names to this specification in the presence of two subscribing witnesses.
